UNITED STATES PATENT OFFICE.

GEORGE CLEMENTS, OF CHICAGO, ILLINOIS, ASSIGNOR TO CLEMENTS MFG. CO., OF CHICAGO, ILLINOIS, A CORPORATION OF ILLINOIS.

VACUUM-CLEANER.

REISSUED

1,392,624.

Specification of Letters Patent.

Patented Oct. 4, 1921.

Application filed June 14, 1911. Serial No. 633,011.

To all whom it may concern:

Be it known that I, GEORGE CLEMENTS, a citizen of the United States, residing at Chicago, in the county of Cook and State 5 of Illinois, have invented a certain new and useful Improvement in Vacuum-Cleaners, of which the following is a specification.

My invention relates to improvements in 10 vacuum cleaners and has for one of its principal objects to provide means for simultaneously disconnecting the suction nozzle and connecting a suction hose with the pumping chamber.

It is illustrated in the accompanying 15 drawings, wherein—

Figure 1 is a side elevation with parts shown in section;

Fig. 2 is a side elevation with the suction 20 hose connected;

Fig. 3 is a bottom plan view of a portion 25 of the structure illustrated in Fig. 1;

Fig. 4 is a cross section along the line 4—4 of Fig. 3.

Like parts are indicated by the same letter 30 in all the figures.

A is a flat cylindrical casing, the interior of which I call the pumping chamber and in it rotates the fan or pumping device A¹.

A² is the discharge outlet therefrom tangentially arranged. The motor casing A³ 35 is attached to one side of the fan casing, and preferably integral with the latter is the suction chamber A⁴ communicating therewith through the port A⁵ and provided with the screw-threaded passageway A⁶ closed by the cap A⁷. The suction passage A⁸ connects with the suction chamber A⁴ at one end and at the other extends into an elongated narrow suction nozzle A⁹, the outer lip of which 40 is preferably provided with the inclined grooves or corrugations A¹⁰. A¹¹ is a spring clip which removably engages the inner lip of the suction nozzle and carries the soft squeegee A¹² projecting outwardly from 45 the nozzle. The pump casing A is pivotally mounted on an eccentric axis between the forks B on the handle B¹ and is limited in its rotational movement by the lugs B² placed on the same side of the center of 50 gravity as the axis of rotation so that the pump casing and its associated parts may be tilted forwardly and downwardly but not be permitted to proceed too far in that direction. The conductors B³ lead from the mo-

tor to the controlling switch B⁴ on the handle, from which switch leads the flexible conducting wire B⁵, which is shown in Fig. 1 as wound about the hooks B⁶ on the handle B¹.

The dust receiving bag C is removably attached to one end of the tangential discharge way A² and at the other end is closed by the spring clip C¹ which is supported by means of the spring C² from the handle B.

D is a hose tube provided with a screw-threaded portion D¹ to engage the screw-threaded port A⁶ in the wall of the suction chamber, an extension D² which passes through the suction chamber and is received into the port A⁵, and a projecting end on 70 which the hose D³ is adapted to be attached. When the hose tube is removed, the cap A⁷ is substituted therefor and the hose tube may be screw-threaded into the outlet so as to deliver air under pressure if desirable. 75

It will be evident that while I have shown in my drawing an operative device, many changes might be made in size, shape and arrangement of the several parts without departing materially from the spirit of my 80 invention.

The use and operation of the invention are quite obvious.

When it is to be used for cleaning floors in the usual manner, the hose tube is removed and the cap A⁷ applied to close the port A⁶. The wire cable is removed from the hooks and the proper connection made, whereupon the motor is set in operation to drive the fan or pump and suck the dust up 90 through the suction nozzle discharging into the bag C, whence the air escapes, leaving the material to be collected behind.

When the device is to be used for wood or other smooth or hard floors, the removable 95 squeegee is attached.

When the hose is to be used the cap A⁷ is removed and the hose tube screwed into position as indicated in Fig. 2. Any kind of a suction device may be attached to one end of the hose, the other end being slipped over the projecting portion of the hose tube.

If the device is to be used for delivering air under pressure, the hose tube is screw-threaded into position in the discharge way as indicated in dotted lines in Fig. 2.

The two arms which project from the

handle are adapted to be thrown up in position when desired as shown in Fig. 1 to form a reel on which the cable can be wound.

The handle is connected a little back of the center of gravity of the device so that the latter tends to tilt downwardly and forwardly, but the engagement of the handle by the stop prevents the device tilting too far forwardly.

10 Certain features shown and described but not claimed herein are made the subject matter of divisional applications Nos. 705,398; 705,399; and 705,400.

I claim:

15 1. A vacuum cleaner consisting of a casing provided with a pump chamber and a suction chamber and separated therefrom by a dividing wall provided with an opening, the walls of the suction chamber terminating in a suction nozzle and the suction chamber provided with an opening registering with the opening in the dividing wall and adapted to receive a cap for closing it or a hose tube extending into the inner opening.

20 2. A vacuum cleaner comprising a pump chamber, a suction chamber, having an outlet opening to the pump chamber, a suction nozzle and an inlet opening, and a removable closure therefor, said openings adapted to receive a connecting inlet tube.

25 3. In a pneumatic cleaner, a casing having a fan chamber, a suction chamber arranged directly below said fan chamber and separated therefrom by a dividing wall provided with an opening, said suction chamber being provided with an opening in the bottom thereof in line with the opening in the dividing wall, and a coupling member adapted to be secured in the opening in the bottom of the suction chamber and having a tubular extension which extends across said suction chamber and into the opening in the dividing wall between said suction chamber and the fan chamber.

40 4. A suction chamber having a fan chamber and a second chamber adjacent to said fan chamber and separated therefrom by a dividing wall provided with an opening, said second chamber being provided with an opening in the wall thereof opposite the opening in the dividing wall, a coupling member adapted to be secured in the opening in the second chamber and having a tubular extension adapted to extend across said second chamber in operative relation to the opening in said dividing wall, and a cover adapted to close the opening in said second chamber when said coupling member

45 is removed.

5. In a pneumatic cleaner, a casing hav-

ing a pump chamber and a second chamber adjacent thereto and terminating in a cleaning device, there being an aperture dividing wall between said chambers and the outer 65 wall of said second chamber having a supplemental opening adapted to receive either a cap for closing it or a coupling communicating immediately with the aperture in the dividing wall.

6. A suction cleaner having a pump chamber and a second chamber separated therefrom by a dividing wall provided with an opening whereby the second chamber may communicate with the first mentioned chamber, the second chamber having an inlet mouth and an opening in operative relation to the opening in the dividing wall, and a coupling member adapted to be applied to the last mentioned opening and having an 80 extension adapted to cut off communication between said first mentioned opening and said inlet mouth.

7. In a cleaner, a casing having a fan chamber, and a suction chamber adjacent 85 thereto and separated therefrom by a dividing wall provided with an opening, said suction chamber communicating with an operating mouth and the wall of said suction chamber having a removable portion, and a 90 hose connection adapted to be secured in direct communicating relation to said opening when said removable portion is displaced.

8. In a vacuum cleaner, the combination of a casing with a nozzle attached thereto, a 95 suction pipe leading therefrom and a suction hose attachment adapted to simultaneously cut off the nozzle connection and connect the hose with the suction.

9. A vacuum cleaner comprising a suction 100 chamber having an oblong primary suction inlet and a secondary circular suction inlet, a pump chamber having a circular inlet from the suction chamber the two circular inlets in substantial alinement, a removable cap 105 for the secondary inlet and a removable inlet tube for the pump chamber adapted to connect the two circular inlets.

10. A vacuum cleaner comprising a suction chamber having a primary suction inlet from the suction chamber means for closing the secondary inlet and pump inlet leading means adapted to connect the pump inlet with the secondary inlet when the closing means is removed and thus disconnect the suction chamber from the pump chamber.

GEORGE CLEMENTS.
